UNITED STATES PATENT OFFICE.

JOHN M. HOGAN, OF OMAHA, NEBRASKA.

DESIGN FOR A WHIST INDICATOR.

Application filed February 12, 1926. Serial No. 16,500. Term of patent 3½ years.

To all whom it may concern:

Be it known that I, JOHN M. HOGAN, a citizen of the United States, residing at Omaha, in the county of Douglas and State of Nebraska, have invented a new, original, and ornamental Design for Whist Indicators, of which the following is a specification, reference being had to the accompanying drawing, forming a part hereof.

Fig. 1 is a side view and Fig. 2 is a front view of the whist indicator, showing my new design.

I claim:

The ornamental design for a whist indicator, as shown.

JOHN M. HOGAN.
